JET MOTOR OPERABLE BY MONOPROPEL-
LANT AND METHOD OF OPERATING ITMaurice J. Zucrow, Altadena, Calif., assignor to
Aerojet Engineering Corporation, Azusa, Calif.,
a corporation of Delaware

Application June 19, 1944, Serial No. 540,959

6 Claims. (Cl. 60—35.6)

1

This invention relates to jet thrust motors and methods of operating it and has for its object to improve the operating performance of such motors.

Jet thrust motors have heretofore been operated by burning fuel in a combustion chamber and causing the exhaust gases to be ejected at high velocities through an exhaust nozzle. Liquid fuels have heretofore been injected into the combustion chamber against the pressure in the chamber for this purpose. Good performance has been obtained by injecting two propellant liquids into the combustion chamber, one a fuel and the other an oxidizer for the fuel. Thus, aniline has been used as a fuel and red fuming nitric acid as an oxidizer and these two liquids have been injected separately into the combustion chamber and caused to impinge against each other. Spontaneous combustion takes place upon the impingement, producing the desired gases which are exhausted as a jet through the exhaust nozzle.

A disadvantage of such spontaneously combustible liquids is that they produce operation at very high temperatures of between 3000° F. and 4500° F., thereby tending to burn the motor when operated for an appreciable time.

Other fuels have been proposed for burning in the chamber which produce higher jet velocities and lower chamber temperatures than the foregoing spontaneously combustible propellants. For example, monopropellants, that is, single sources of propellant liquid, such as nitromethane or a mixture of nitromethane and nitroethane have been used. These burn at the desired lower temperatures and produce the desired higher jet velocities, but they are not as easily ignitable as the more spontaneously combustible higher temperature fuels, so have required more special means of igniting, for example, an elevated igniting temperature.

In accordance with my invention I am able to make use of a fuel which burns at lower temperature and higher velocities such as the monopropellant nitromethane, by first igniting easily spontaneously combusted propellants and thereby heating the chamber or a refractory member in it which can be brought up to a temperature required to ignite the lower temperature burning fuel. For example if the initial propellants be aniline and red fuming nitric acid, these can be burned for a couple of seconds, long enough to heat the chamber or a refractory member in it to around 300° F. which is a sufficiently high temperature for igniting nitromethane.

2

A feature of my invention is the use of a temperature controlled valve to disconnect the starter propellants when the temperature is brought up to the desired level and then ejecting the second lower temperature burning propellant.

In this way I am enabled to obtain the easy igniting characteristics of propellants such as aniline and red fuming nitric acid and to obtain during most of the time of operation the higher jet velocities and lower chamber temperatures of the more difficultly ignitable propellants such as the nitroparaffins.

My invention will be better understood from the following description when taken in conjunction with the sheet of drawing in which:

Fig. 1 is an elevational view in cross section of my invention;

Fig. 2 is an end view of Fig. 1; and

Fig. 3 is a cross sectional view along line 3—3 of Fig. 1.

Similar numerals refer to similar parts in the views.

The motor shown in Figs. 1 and 2 comprises a spherical portion 1 which is the combustion chamber and an exhaust nozzle 2. The combustion chamber is made of two pieces, a hemispherical portion 3 which is welded to another hemispherical portion 5 at 4. The hemispherical portion 5 is somewhat elongated containing a flange 7 welded thereto at 6. Flange 7 contains internal threads 8 into which the exhaust nozzle 2 is screwed. The exhaust nozzle 2 has a collar 10 provided with threads and a shoulder flange 11. The shoulder flange 11 is recessed as shown at 12. The wall of the exhaust nozzle 2 contracts toward a constricted portion 13 from recess 12. The constricted portion 13 flares outwardly to an enlarged portion 14. Another flange 15 is welded to the enlarged portion 14. The flange 15 continues substantially the general outline of the exhaust nozzle forming a recess 16 and a thickened section 17 which provides the necessary metal for the threads of screws 18. The flange 15 is machined to receive bolt ring 19 and machined completing the outline of the exhaust nozzle at 20.

In Figs. 1, 2 and 3 the exhaust nozzle is surrounded by a jacket 22 arranged to provide a fluid flow spirally from the fluid inlet at the extreme end of the exhaust nozzle toward a chamber around the combustion chamber. A spiral member 21 is formed integrally with the wall of the exhaust nozzle 2 or may be welded to it. A pair of solid members 80 and 81 are placed around the spiral at the nozzle, the two halves being

bolted together by bolt 62 and nut 63. The inner curved surfaces of members 60 and 61 fit against the edges of the spiral convolution so that the convolution forms a spiral passageway for the passage of fluid spirally around the nozzle from a fluid inlet at pipe 53 to the fluid chamber A around the combustion chamber. The convolution near the exhaust end 20 of the nozzle is made of greater height than at the constricted throat of the nozzle. Thus, convolution 25 is higher than convolution 24 which serves to space members 60 and 61 further from the nozzle wall at the exhaust end than at the throat. Thus, the area for fluid passage is greater at the exhaust end than at the throat. The outer peripheries of members 60 and 61 coincide with the inner surface of a jacket 22. One or a plurality of slots 27 are machined around members 60 and 61 and into each slot an O ring 28 is snapped providing a fluid tight contact between members 60 and 61 and the tubular jacket 22. The fluid inlet is provided through a nipple 29 to the jacket at the exhaust end of the nozzle 2, this entrance communicating with the spiral convolution which is nearest the exhaust. The tubular jacket 22 is welded to the bolt ring 19. By inserting screws 18 through the bolt ring 19 and screwing them into the flange 15 the exhaust nozzle 2 is thereby fastened to the tubular member 22.

The tubular member 22 is provided with a ring 30 which acts as a retainer for another O ring 31. The O ring 31 fits between tubular member 22 and another tubular member 32 surrounding member 22. Tubular member 32 contains an interior ring 33 which provides another retainer for the O ring 31. A tubular member 34 flaring out and forming a hemispherical shape 35 surrounds the hemispherical elongated member 5 and is welded to tubular member 32 providing a chamber A between members 5 and 35 through which a fluid may circulate.

Another hemispherical member 35a is welded to the hemispherical member 35 at 70. Continuation of chamber A is provided between member 35 and member 35a. In the extreme portion of the spherical combustion chamber I show a multiway L 71 welded to the hemispherical member 35a which is in communication by conduit 56 with the injector valve 54, and in further communication by corresponding conduits 56a and 56b with the other two injector valves, respectively, a part of these conduits 56a and 56b being shown in Fig. 2.

A hemispherical refractory liner 72 is placed into the hemispherical combustion chamber and backed by the refractory liner 73. Liners 72 and 73 are held in place by flange 7 and collar 10 which is screwed into flange 1.

The refractory lining may be any of the following: tungsten, tungsten carbide, silicon carbide, boron carbide, calcium oxalate, carbon (graphite), magnesium oxide, molybdenum carbide, zirconium carbide, zirconium oxide or any other standard refractories such as mullite, Transite, mixture of carbon and asbestos, or other like substances.

In the upper portion of the hemispherical member 35 a tubular member 36 having a flange 37 is welded thereto; member 36 protrudes through chamber A into the hemispherical portion 5 to 70 which it is also welded.

A dual injector is provided comprising a cylindrical member 38 having a flange 39, an opening in one end and a wall 40 in the other end. A flared nipple (not shown) is provided in the 75

left hand side of flange 39 to which a conduit 41 may be attached in the conventional manner and secured thereto with nut 42. A cylindrical member 43 having on one end a flared portion (not shown) and a thread below the flare provides conventional means for attaching a conduit 50 securing it with nut 51. Member 43 has a concentric opening to the wall 44 where a small orifice 45 is provided. Wall 44 is formed to provide an inclined surface 46 having two or more orifices 47 therein. Wall 44 forms a horizontal surface 48. The horizontal surface 48 abuts against the cylindrical member 38 and is welded thereto. Member 43 passes through the wall 40 and is likewise welded thereto. The whole dual injector is inserted into the tubular member 36 and bolted to flange 37 with screws 14. A gasket 75 makes the connection pressure tight.

In the lower portion of member 35 there is a tubular boss 54 having a shoulder and a smaller cylindrical portion 55. This portion 55 is inserted into member 33 passing through chamber A into the hemispherical member 5 and is welded to both hemispherical members 35 and 5. Boss 54 is provided with a flared and threaded nipple (not shown) for connecting a conduit 56 which is secured by nut 57. A concentric threaded hole is provided in boss 54 into which an injector valve 58 is screwed. Injector 58 is made of hexagonal stock turned down providing a head and a threaded portion which is screwed into the boss 54. The head rests against a washer 59 which makes the injector valve 58 pressure tight. Hole 64 is drilled at assembly when the injector valve 58 is inserted. A concentric hole 65 is provided in the injector running to a wall 66 which contains an orifice 67 into which a valve 68 is fitted. Valve 68 has an enlarged piston 69 sliding in the concentric hole 65 and is under the pressure of a spring 80. The spring pressure may be adjusted by an inserted set screw 81. Guide 68a of the valve 68 passes through the set screw 81. Although only three injector valves are shown it will be understood that any number of such injectors may be provided. There is provided a valve 52 arranged to prevent fluid from flowing into the dual injector through conduits 41 and 50 when fluid is flowing into the motor through pipe 53; and vice versa. This valve 52 comprises a valve chamber 90 having three inlet ports 91, 92 and 93 and respective outlet ports 94, 95 and 96. The valve chamber is made slightly tapered, as shown, and is provided with a correspondingly tapered valve stem 97 held snugly in the valve chamber by means of a compression spring 98 compressed between the top of the stem and the cap 99. The valve stem is provided with three holes 100, 101 and 102. Holes 100 and 101 are parallel to each other and hole 102 has its axis at 90° to the axis of holes 100 and 101. Holes 100 and 101 are adapted to provide communication respectively between ports 91 and 94 and between ports 92 and 95 as shown, when the valve stem holes are lined up with the ports. Hole 102 is adapted to provide communication between ports 93 and 96 when the hole 102 is lined up with these ports. When valve handle 103 is turned to the position shown the valve stem is in the angular position to provide flow through conduits 41 and 50 but not through conduit 53. Turning the valve stem 90° would provide flow through conduit 53 but not through conduits 41 and 50.

When starting the motor the valve 52 is operated which commences the flow of small

amounts of the fuel and the oxidizer. By permitting only small amounts of the fuel and oxidizer their spontaneous combustion is thereby assured. The correct proportion should be three parts of oxidizer to one part of fuel. The oxidizer flows through conduit 41 (Fig. 2) into the dual injector and is injected through nozzles 47 (Fig. 1) into the combustion chamber. Fuel flows through conduit 50 (Fig. 2) and is injected through nozzle 45 (Fig. 1) into the combustion chamber. Both streams meet at B igniting spontaneously and the hot gases of combustion come in contact with the refractory liner 72 which is heated thereby. As soon as the temperature of the refractory liner 72 reaches the temperature required for combusting the monopropellant the valve 52 shuts off the flow of the fuel and the oxidizer and turns on the monopropellant which flows through conduit 53 (Fig. 2) into the convolutions of the spiral 21 (Fig. 1) and through the chamber A and is distributed through the multiple way L 71 into the respective injector nozzles. The monopropellant is injected into the combustion chamber by three streams which impinge at C thereby further dispersing it. When the monopropellant hits the heated refractory liner 72 it is combusted. The products of combustion escape through the exhaust nozzle delivering thereby the desired thrust. The thrust of the motor may be varied by manipulating a control valve 76 (Fig. 2) inserted in the monopropellant conduit between the valve 52 and the motor.

The method of leading the monopropellant through chamber A keeps the temperature of the spherical combustion chamber within 150° C. or a little above.

From the foregoing description it can readily be seen that I have provided a jet thrust motor which may operate for considerable periods of time.

I claim:

1. In combination with a jet motor having a combustion chamber and an exhaust nozzle, a plurality of propellant injectors, at least one of the injectors having a single injection orifice for injecting a monopropellant into the chamber, another of the injectors having at least two injection orifices, one for a fuel and one for an oxidizer, a conduit for leading fuel and a conduit for leading oxidizer to the last-mentioned injector, a conduit for leading the monopropellant to the monopropellant injector, and a valve connected with the conduits for preventing the monopropellant from flowing through its injector when the fuel and oxidizer are flowing through their injectors and for preventing the fuel and oxidizer from flowing through their injectors when the monopropellant is flowing through its injector.

2. A combination according to claim 1 in which means are provided for maintaining the monopropellant injector orifice closed when the fuel and oxidizer are flowing through the dual injector.

3. In combination with a jet motor having a combustion chamber and an exhaust nozzle, a plurality of propellant injectors, at least one of the injectors having an injector orifice for injecting a monopropellant into the chamber, a jacket around the nozzle and combustion chamber providing a cooling chamber through which the monopropellant flows to its injector, an inlet to the cooling chamber, another of the injectors

having at least two injection orifices, one for a fuel and one for an oxidizer, a conduit for leading fuel to the dual injector and a conduit for leading oxidizer to the dual injector and a conduit for leading the monopropellant to the inlet, a valve for closing the monopropellant conduit when the fuel and oxidizer conduits are opened and for opening the monopropellant conduit when the fuel and oxidizer conduits are closed.

4. The method of operating a thrust motor having a combustion chamber and an exhaust nozzle which comprises introducing streams of aniline and red fuming nitric acid into the chamber, and thereby spontaneously combusting them, thereafter stopping the supply of said aniline and acid and immediately thereafter combusting within said chamber a monopropellant fluid consisting of nitromethane, and exhausting the products of combustion through the nozzle.

5. The method of operating a thrust motor having a combustion chamber and an exhaust nozzle which comprises introducing streams of aniline and red fuming nitric acid into the chamber and thereby spontaneously combusting them, thereafter stopping the supply of said aniline and acid and immediately thereafter combusting within said chamber a monopropellant fluid consisting of a mixture of nitromethane and nitroethane, and exhausting the products of combustion through the nozzle.

6. The method of operating a thrust motor having a combustion chamber and an exhaust nozzle which comprises initially heating the chamber by combusting in it a spontaneously combustible propellant fluid, thereafter stopping the supply of said combustible fluid and immediately thereafter injecting into the chamber a monopropellant fluid which ignites at the temperature to which the chamber has been raised, and exhausting the products of combustion through the nozzle.
